US0D1021120S

(12) **United States Design Patent** (10) **Patent No.:** **US D1,021,120 S**
(45) **Date of Patent:** **** Apr. 2, 2024**

(54) **LED PANEL FOR A PHOTODYNAMIC THERAPY LAMP**

(71) Applicant: **Biofrontera Pharma GmbH**, Leverkusen (DE)

(72) Inventors: **Markus Osterloh**, Leverkusen (DE); **Ben Novak**, Leverkusen (DE); **Hermann Lubbert**, Leverkusen (DE)

(73) Assignee: **Biofrontera Pharma GmbH**, Leverkusen (DE)

(**) Term: **15 Years**

(21) Appl. No.: **29/812,081**

(22) Filed: **Oct. 19, 2021**

Related U.S. Application Data

(63) Continuation of application No. 17/215,785, filed on Mar. 29, 2021, now Pat. No. 11,235,169, and a continuation of application No. 17/071,496, filed on Oct. 15, 2020.

(57) **CLAIM**

The ornamental design for a LED panel for a photodynamic therapy lamp, as shown and described.

DESCRIPTION

FIG. 1 is a top perspective view of a LED panel for a photodynamic therapy lamp, showing our new design;

FIG. 2 is a top view thereof;

FIG. 3 is a bottom view thereof;

FIG. 4 is a left side view thereof;

FIG. 5 is a right side view thereof;

FIG. 6 is a rear view thereof; and,

FIG. 7 is a front view thereof.

The broken lines shown are not a part of the claimed design.

1 Claim, 5 Drawing Sheets
